WHEELED BOOK CARRIER

Karl Edgar Frye, Lincoln, Nebr.

Application May 20, 1953, Serial No. 356,229

2 Claims. (Cl. 280—47.26)

This invention relates to a device for transporting books having particular utility in libraries and other places where a great number of books are daily trucked over short distances.

Manually operated book carts which are employed to haul medium and large size books from one local point to another should have a structure designed to meet certain desirable objectives. In view of the relatively large cumulative weight of stacked books, the cart should be as light as possible without sacrificing other desirable features such as strength and durability. The cart must be capable of securely retaining the books in place during travel and yet permit their easy access and removal. This invention contemplates an improved book carrier which anticipates these desired features.

Generally the book carrier comprises a two wheel device which provides a rearwardly inclined book supporting plate directly secured by a bracket to the wheel axle having a foot projection secured to the underside of its forward portion insuring that the books supported thereon will not pitch forward when the carrier is in an upright position. The books are stacked on this plate and are prevented from falling through the device rearwardly by at least one and preferably two pairs of complementary side frame bars. The relative placement of these complementary bars with respect to each other is an important feature of the invention. Assuming that the carrier is used to transport books of library edition size, as opposed to the pocket or bantam sizes, the distance separating the side frame bars of one pair is made less than the short side of most of such editions intended to be carried by the book cart. It is thus impossible for the books to fall through the back of the cart. The books are stacked cornerwise. The complementary bars can be spaced sufficiently far apart that two sides of each book are supported to prevent the books from escaping to either side. Accordingly the stacked books are safely supported without the need of an additional bar supported at the rear of the book supporting plate which interferes with the stacking and removal of the books. Since for large carriers these bars are the largest single components, a significant saving in weight is effected.

As a further precaution against side movement a second pair of complementary bars may be provided. These bars are spaced farther apart than the first pair of bars and disposed forwardly thereof. The two pairs of bars thus provide a V-shape channel for the stack of books.

The means for supporting the book supporting member and side bars are specially designed to lend strength to the carrier. These and other features of the invention will be apparent on reading the description in connection with the drawings in which:

Fig. 1 is an isometric of the book carrier;

Fig. 2 is a side elevation of same;

Fig. 3 is a section in plan taken on line 3—3 of Fig. 2 and

Fig. 4 is a section taken on the line 4—4 of Fig. 1.

A book supporting member 5 is secured to sleeve 6

2

by means of a pair of side tubular brackets 7 and 8. The member 5 is rectangular in shape and is disposed with one corner directed toward the sleeve 6. Its interior portion is partially open to eliminate unnecessary weight.

5 A flat piece 10 extends between two corners as a book support. The member 5 is rearwardly inclined and has secured to the underside of its forward portion a foot projection 11.

Attached to the two sides of the book supporting member 5 nearest the sleeve 6 is a pair of complementary side frame bars 12 and 13 extending vertically with respect to the member 5. These bars are spaced sufficiently close together that books of ordinary library edition size can not pass between them regardless of their disposition. For example, if the bars were spaced no greater than five inches apart, very few books commonly seen on library shelves would be capable of falling through the back of the carrier. The placement of the bars is such that they serve to prevent the books from escaping from the carrier either to the side or to the rear. As shown a second pair of complementary side frame bars 14 and 15 are disposed in parallel to the first pair being supported by the book supporting member 5 at its intermediate corners. The two pairs of side frame bars accordingly 15 form a V-shaped trough which has no need for any type of weight contributing closure at its apex.

The side frame bars are connected by two spanning elements 16 and 17 at the top of the device. A handle 18 is joined at the juncture of the spanning elements. Supporting bars 19 and 20 connect the side frame bars on each side of the carrier.

Because the book supporting member 5 and the side frame bars bear the direct burden of the book load, separate means are provided to support them. While the brackets 7 and 8 support the member 5 with respect to the sleeve 6, the side bars are independently secured thereto by braces 21 and 22. Each supporting means therefore strengthens the carrier without depending on each other to accomplish their special function.

40 An axle 23 extends through the sleeve 6. The ends of the axle project through the sleeve and wheels 24 and 25 and are mounted for rotation thereon.

It is obvious that alterations may be effected in the structural design of the above described book carrier 45 within the scope and principle of the invention by one skilled in the particular art. It is understood that the invention is to be defined and limited only in accordance with the appended claims.

What is claimed is:

50 1. A hand truck for books or the like comprising a substantially square platform, a pair of upright parallel bars attached to the top of the platform at opposite corners thereof, a second pair of parallel bars disposed in a plane parallel to that of the first pair and attached to the top of the platform at the marginal portions thereof at the rear of and extending parallel to the first pair, whereby the two pairs of bars define a rectangular V-shape rack coincident with the rear half of the platform, rearwardly extending brackets secured to the platform, a wheel axle carried by the brackets, a foot carried by and depending from the front corner of the platform of a length to maintain the truck in rearwardly tilted position, and two members disposed in a V and joining the top ends of the two pairs of bars.

60 65 2. A hand truck for books or the like comprising a platform composed of angle members joined with one external face upward to form a hollow square having a marginal supporting surface and a flat piece extending diagonally across the square in the plane of said surface and secured to the opposite corners of the platform members, a pair of parallel upwardly extending bars attached at their lower ends to the said opposite corners of the

platform supporting surface, a second pair of parallel bars disposed in a plane parallel to the first pair and attached at their lower ends to the platform supporting surface at the rear of the first pair and extending upward parallel to the first pair, the diameter of the rods being less than the width of the supporting faces of the angle members, whereby the two pairs of bars define a rectangular V-shape rack open at the apex, rearwardly extending brackets secured to the said opposite corners of the platform, a wheel axle carried by the brackets, and

a foot depending from the front corner of the platform attached to the under face of the angle members and of a length to maintain the truck in rearwardly tilted position.
